The ornamental design for a bottle for a laboratory analyzer, as shown and described.

DESCRIPTION

FIG. 1 is a side elevational view of a bottle for a laboratory analyzer showing our new design, the opposite side elevational view being a mirror image thereof;

FIG. 2 is a bottom plan view;

FIG. 3 is a top plan view;

FIG. 4 is a front elevational view;

FIG. 5 is a rear elevational view; and,

FIG. 6 is a perspective view.
